(57) **CLAIM**

The ornamental design for an electronic device charger, as shown and described.

DESCRIPTION

FIG. 1 is an upper front perspective view of an electronic device charger.

FIG. 2 is a right side view showing the design of FIG. 1.

FIG. 3 is a front view showing the design of FIG. 1.

FIG. 4 is a rear view showing the design of FIG. 1.

FIG. 5 is an upper rear perspective view showing the design of FIG. 1.

FIG. 6 is a lower right side perspective view showing the design of FIG. 1.

FIG. 7 is a lower front perspective view showing the design of FIG. 1.

FIG. 8 is a top view showing the design of FIG. 1; and,

FIG. 9 is a bottom view showing the design of FIG. 1.

The broken lines are for the purpose of illustrating portions of the electronic device charger that form no part of the claimed design.
